MIXING MILL

Raymond W. Allen, Akron, Ohio, assignor to The Firestone Tire & Rubber Company, Akron, Ohio, a corporation of Ohio

Application September 29, 1939; Serial No. 297,061

9 Claims. (Cl. 18—2)

This invention relates to mixing mills for the mixing or warming of plastic material such as rubber composition, and more especially it relates to automatically operating mills wherein a blade moving relatively of one of the mill rolls effects the stripping of a sheet of plastic material therefrom and the feeding of the stripped material back into the bite of the rolls whereby optimum mixing or warming of the plastic composition is effected.

In apparatus of the character mentioned, as heretofore provided, the blade has been moved into and out of engagement with the mill roll by means of a fluid pressure operated cylinder, the latter being mounted upon a carriage that has a reciprocatory movement longitudinally of the mill roll, a reversible electric motor being employed for moving the carriage. Reversing switches at the ends of the carriage's traverse usually were provided for reversing the motor, and valve-operating mechanisms usually were positioned along the course of the carriage for operating the fluid pressure cylinder carried thereby.

The chief objects of the invention are to provide an improved mixing mill of the character mentioned wherein the use of fluid pressure operated cylinders is obviated; to obviate the use of a plurality of valves such as are necessary with fluid pressure operated apparatus; to provide motor driven means for effecting the raising and lowering of the scraper blade of the mill; to provide means for yieldingly applying the scraper blade to a mill roll; and to provide automatically operated switch means for operating the electrically driven mechanism of the apparatus in determinate time sequence. Other objects will be manifest as the description proceeds.

Of the accompanying drawings:

Figure 1 is a front elevation of apparatus embodying the invention, parts being broken away to reveal underlying mechanisms;

Figure 2 is a section, on a larger scale, on the line 2—2 of Figure 1, some parts being shown in elevation;

Figure 3 is a section on the line 3—3 of Figure 2;

Figure 4 is a sectional detail view on the line 4—4 of Figures 1 and 6, parts being shown in elevation;

Figure 5 is a fragmentary sectional view on the line 5—5 of Figure 6;

Figure 6 is an end elevation of the electric switches and their operating mechanism as viewed from the left of Figures 1 and 4;

Figure 7 is a diagrammatic view showing the course of the scraper blade;

Figures 8, 9, and 10 are detail elevations of a pair of switches and their operating means, as viewed from the line X—X of Figure 4, in various phases of a cycle of operation of the apparatus; and

Figures 11, 12, 13, and 14 are detail elevations of another switch and its operating means, as viewed from the left of Figures 1 and 4, shown in different phases of a cycle of operation of the apparatus.

Referring now to the drawings, especially Figures 1 and 2 thereof, there is shown a rubber-working mill comprising end frames 10, 10 in which are journaled a pair of laterally disposed horizontal rolls 11, 12 that are geared together and driven in unison by the usual driving means (not shown). The rolls 11, 12 are adapted to form a sheet or sleeve 13 of plastic composition from a bank 14 of such composition that is fed into the bite between said rolls, the sheet 13 being shown herein as formed on the front roll 12. As shown, the mill is associated with a superposed "Banbury" mixer of well known construction wherein the various constituent ingredients of a batch of rubber composition initially are assembled and co-mingled, the arrangement being such that the batch may be discharged from the bottom of the "Banbury" and directly received in the bite of the mill rolls 11, 12. The "Banbury," which is designated as a whole by the numeral 140, comprises respective hollow end housings 15, 15 that are superposed upon the respective end frames 10 of the mill. Of course, the "Banbury" portion of the mill may be omitted, if desired.

Mounted upon the confronting walls of the end housings 15, 15, interiorly of the said end housings, are bearing plates 18, 19, the former being in the end housing at the left end of the mill as viewed in Figure 1, and the latter being in the end housing at the right end of the mill. The wall of each housing structure 15, back of the bearing plates 18, 19, is apertured to receive a pair of vertically aligned, annular, apertured sockets 20, 20 that are formed on the rear face of each bearing plate, the sockets of one bearing plate being axially aligned with the sockets of the other. Received in said sockets 20 are the reduced end portions of a pair of parallel horizontal guide bars or shafts 21, 21, said guide bars being disposed in the same vertical plane above the mill roll 12. The guide bars 21 slidably support a carriage that is movable longitudinally

thereof, said carriage as a whole being designated by the numeral 22.

For propelling the carriage 22 back and forth along the guide bars 21, a feed screw 24 is provided, which feed screw is positioned between and parallel to said guide bars 21, and extends through a portion of the carriage 22 with which it has threaded engagement whereby rotation of the screw in opposite directions effects lateral movement of the carriage along the guide bars in opposite directions. Opposite end portions of the screw 24 are unthreaded and extend freely through suitable apertures in confronting walls of the end housings 15, the left end of the feed screw being journaled in a bearing 25, Figure 4, carried by the bearing plate 18. The right hand end of the screw 24 is journaled in a suitable bearing carried by the bearing plate 19, and has a terminal portion that projects beyond said bearing and is provided with a gear 26 thereon. The latter is in mesh with a pinion 27 mounted upon the shaft of a reversible motor 28, which motor is supported upon a bracket 29 affixed to the bearing plate 19. The ratio of the pinion 27 to the gear 26 may be varied to obtain the desired mixing speed, or the motor 28 may be of variable speed. Access to the motor 28 is had through an aperture 30 in the outer wall of the housing 15, which aperture is provided with a cover plate 31. The motor 28 is driven alternately in opposite directions, and control means for reversing the direction of rotation of the motor presently will be described.

The carriage 22 is a hollow structure comprising a rearwardly disposed bearing bracket portion 33 that engages the slide bars 21, and a transversely arcuate cover plate 34 on the front thereof. The structure is open at top and bottom, and mounted in its upper opening is a lower housing 35, and mounted upon the latter is an upper housing 36, the latter being formed with a tubular axial extension 37 that extends upwardly and is closed at its upper end. The lower housing 35 carries an axially disposed bearing 38 and the upper housing 36 carries an axially disposed bearing 39, said bearings rotatably supporting a nut 40 by engagement with opposite end portions thereof. Mounted upon the exterior of the nut 40 is a gear 41 that is meshed with a pinion 42, the latter being mounted upon the lower end of the shaft 43 of a motor 44. Said motor is supported upon the tubular extension 37 of upper housing 36, the shaft 43 extending through said housing. The motor 44 is reversible, and is supplied with electric current through a three-conductor cable 45 that extends from said motor to a trolley collector 46 that is supported upon the carriage 22, directly above the upper guide bar 21. Said trolley collector is positioned within a trolley duct 47 that is mounted upon the bottom of the "Banbury" structure 14, said duct being open at the bottom to enable the collector 46 to move longitudinally thereof. The trolley collector and duct are of well-known construction, and are arranged to supply electric current to the three conductors of cable 45 at all positions of the carriage 22. Control means for reversing the direction of rotation of the motor 44 according to the position of the carriage in its traverse of the mill is included in the circuit of motor 44 and presently will be described. The said motor circuit also includes a torque-limit relay (not shown) that serves to disconnect the electric current thereto when the driving torque exceeds a determinate maximum limit.

Threaded through the nut 40 is a feed screw 50, the same having threads thereon for about two-thirds the distance from its upper end, the lower third of the screw being smooth, there being a flange 51 formed at the juncture of the threaded and the smooth portions, said smooth portion projecting through the open lower end of the carriage structure. The arrangement is such that rotation of the nut 40 will cause the feed screw 50 to move axially up or down according to the direction of rotation of the nut, the hollow extension 37 of the upper housing 36 receiving the screw when it is moved upwardly. Formed in the bracket portion 33 of the carriage, along the parting plane thereof and its cover 34, are oppositely disposed, parallel slideways 52, 52, Figure 3, in which a slide 53 is mounted for sliding movement parallel to the screw 50. The slide 53 is mostly of transversely arcuate shape so as to extend about the screw 50 in spaced relation thereto, but intermediate the upper and lower ends of the slide there is formed a forwardly projecting ledge or shelf 54 through which the smooth lower end portion of the screw extends, there being a bushing 55 in said shelf about the screw to reduce friction as the slide and screw move relatively of each other. Mounted upon the smooth end portion of the screw 50 in abutting relation to the flange 51 is a collar 56, and mounted upon said screw between said collar and the ledge 54 of the slide is a compression spring 57, the latter being encased at its lower portion in a protective sleeve 58. Mounted upon the front of the slide 53 at the lower end thereof is a blade holder 59 that has limited adjustability in an up and down direction, the upper margin of said holder abutting a pair of set screws 60, 60, Figure 1, that are threaded into the overhanging ledge 54, and which assist in retaining the holder in adjusted position against pressures to which it is subjected during use. A scraper blade 61 is secured to the front face of the holder 59, the lower margin of said blade constituting a cutting edge that extends below the bottom of said holder, in position for engagement with the mill roll 12. The blade holder 59 is formed with a central slot 62 extending downwardly from its upper margin, and the holder 53 is recessed behind said slot, as shown in Figure 1, to receive a slide block 63 that is mounted upon the lower end of screw 50, said block being slidable in said slot 62 and in said recess behind the same. The end of screw 50 is squared to receive said slide block, the arrangement being such that rotation of said screw is prevented, yet axial movement of the screw relatively of the slide is permitted. Thus downward movement of the screw 50 also moves the slide 53 downwardly until the blade 61 engages the mill roll 12, further downward movement of the screw before stopping resulting in compression of the spring 57. The latter assures more even pressure of the blade against the mill roll notwithstanding unevenness of the surface of said roll. It also serves to increase the driving torque of the motor 44, which torque ultimately effects the automatic stopping of the motor.

As previously stated, the reversible motor 28, by driving the screw 24 alternately in opposite directions, impels the carriage 22 back and forth longitudinally of the mill rolls 11, 12, and the reversible motor 44, by alternately driving the nut 40 in opposite directions, raises and lowers the screw 50 and with it the scraper blade 61. These operations are effected in determinate time relation and impart to the scraper blade a

compound movement that causes it to traverse a course that is diagrammatically illustrated in Figure 7. From this figure it will be apparent that as the movement of the blade carries it toward the end of the roll, it is lifted from the roll for a brief interval, and then lowered into engagement with the roll before the end of the latter is reached. Upon reaching the end of the roll the direction of lateral travel of the blade is reversed and it moves toward the opposite end of the roll while still engaged therewith, and upon approaching the opposite end of the roll is again lifted off the roll and again lowered into engagement therewith, in the same manner as previously described. When the blade 61 is moved toward the roll 12, near the end of the roll, it forces and cuts its way through the sheet of material 13 thereon. Then as its direction of lateral movement is reversed and it moves toward the opposite end of the roll it forces its way through the sheet 13 and piles it up somewhat at its leading edge, as is best shown in Figure 1, and lays the stripped material in convolutions or folds that are disposed obliquely of the roll. When the blade subsequently rises, the fold of stripped material passes substantially lengthwise into the bite of rolls 11, 12 whereby intimate mixing and warming of the ingredients thereof is effected.

The mechanism for controlling the driving of the motors 28, 44, and for reversing the direction of their drive in determinate time relation is shown in detail in Figures 4 to 14, to which attention now is directed. Mounted upon the bearing plate 18, at the left end of the apparatus is a closed gear case 65 into which the terminal portion of the feed screw 24 extends, said terminal portion having a gear worm 66 mounted thereon. The worm 66 is meshed with a worm gear 67 that is mounted upon one end of a countershaft 68, the latter being disposed transversely of the axis of worm 66, and journaled in the opposite lateral walls of the gear case 65. Mounted upon the shaft 68 near the middle thereof is a gear worm 69 that is meshed with a worm gear 70, the latter being mounted upon a cam shaft 71. The said cam shaft is disposed parallel to the feed screw 24, and is journaled at one end in a bearing 72 in bearing plate 18, and is journaled in its medial region in a bearing 73 that is mounted in the wall of gear case 65, said cam shaft extending through the latter and having a substantial portion of its structure projecting therefrom.

Keyed to the projecting end portion of the shaft 71, exteriorly of the gear case, is a hub structure 75 that is formed with a radially extending circumferential flange 76. Secured to the inner end face of the hub 75 by means of a pair of cap screws 77, 77 is a cam plate 78, said screws passing through respective arcuate slots 79, 79 in the camplate to enable the latter to be adjusted angularly, relatively of said hub. Mounted upon the front face of cam plate 78 is a cam 80, and mounted upon the rear face thereof is a cam 81, both of said cams projecting beyond the periphery of the cam plate. Said cams as shown are positioned upon centers that are substantially 90°-270° apart from each other, but one of them is adjustably mounted so that the said angle may be altered to a limited extent.

The gear case 65 is formed integrally with a bracket 84 that is disposed above the cam shaft 71, and which carries two electric switches that are in the electrical circuit of the reversible

motor 28 and serve to reverse the latter as said switches are operated in alternation. Said switches are of any known or desired construction comprising two make and two break contacts (not shown) and are enclosed in suitable receptacles 85, 86, the switch in the former reversing the motor 28 when the carriage 22 is at the right end of the screw 24 and the switch in receptacle 86 reversing the motor when the carriage is at the opposite end of the screw. The switch 85 is provided with an operating plunger 87 that is engaged with an operating lever 88 having a cam roller 89 in its free end, said cam roller being disposed in the orbit of the front cam 80. In like manner the switch 86 is provided with an operating plunger 90 that is engaged with an operating lever 91 having a cam roller 92 in its free end, which cam roller is disposed in the orbit of the rear cam 81. The cam rollers 89, 92 are disposed substantially 26° apart with relation to the axis of cam shaft 71, and this distance added to the 270° separation of cams 80, 81 makes an angle of 296° through which the cam shaft is required to rotate during each half-cycle of operation, that is, in moving from the position shown in Figure 9 to the position shown in Figure 10 for example, during which half-cycle the carriage 22 moves from one end of its traverse to the other. This result is accomplished by the worm gears 66, 67 and 69, 70 which provide a 250 to 1 reduction between the feed screw 24 and the countershaft 71, the pitch of the threads of screw 24 being such as to impel the carriage 22 substantially throughout the length of its threaded portion while the countershaft turns about 296°. The arrangement is such that the countershaft continuously oscillates through an angle of 296° to cause cam 80 to operate switch 85 and cam 81 to operate switch 86 in alternation, and thus periodically to reverse the motor 28 and screw 24 whereby carriage 22 moves back and forth over the mill rolls.

Oscillation of countershaft 71 also is utilized for reversing the motor 44 in determinate time relation to the reversal of motor 28 so as to raise and lower scraper blade 61 at determinate regions of the carriage's traverse, and to this end an annular cam plate 95 is mounted upon the hub 75 and secured to the outer face of its flange 76 by cap screws 96 that extend through an arcuate slot 97 in said hub flange to provide angular adjustability of said cam plate. Projecting laterally from the outer face of cam plate 95 is a driving stud 98 that projects through an arcuate slot 99 formed in a disc cam 100, the latter being journaled upon a bearing 101 on the terminal end of the countershaft 71. The slot 99 is concentric with the axis of said countershaft and is 140° in length. The stud 98 is received in one of a plurality of arcuately positioned holes 95a in the cam plate 95 (Figures 11-14). Diametrically opposite the middle of slot 99 the periphery of the cam 100 is formed with a recessed or depressed cam surface 110. Below the cam shaft 71 on the gear case 65 an integral bracket 102 is formed, which bracket carries a receptacle or switch box 103 in which is contained an electric switch (not shown) that is in the electrical circuit of the reversible motor 44. The switch is provided with an operating plunger 104 that is engaged with an operating lever 105 having a cam roller 106 journaled in its free end, said cam roller being disposed in vertical alignment with the cam shaft 71, and urged upwardly against the periphery of cam 100. The switch in receptacle 103 is known

as the vertical movement switch, and is so constructed and arranged that when the plunger 104 is out or raised, as shown in the drawings, the motor 44 rotates in the direction that elevates the scraper blade 61, and when the said plunger is in or is depressed the motor rotates in the opposite direction so as to lower the scraper blade, rotation of the motor in either direction continuing until the torque in the motor is sufficient to operate the torque-limit relay, whereupon rotation ceases. When the cam 100 is so angularly positioned that the cam roller 106 is on the depressed cam surface 110 thereof, the plunger 104 is in elevated position and the motor 44 is caused to rotate in the direction that raises the blade 61. The length of the cam surface 110 is such that the plunger 104 remains in elevated position while the cam 100 rotates through an angle of 43°, the time interval during which said plunger is raised being sufficient for the motor 44 to raise the blade 61 to maximum height and to stop. The torque that effects the stopping of motor 44, as the scraper blade is raised, is created by the compression of spring 57 after the collar 56 on screw 50 engages the lower end of lower housing 35.

As previously stated, the cam shaft 71 oscillates through an angle of substantially 296°, as does the hub 75 keyed thereto. Thus the stud 98 projecting from the flange of said hub and through slot 99 of cam 100 is adapted to oscillate the latter, but to a lesser degree, namely 156° (296° minus 140°), the cam surface 110 being in the medial region of the 156° of cam surface that engages the cam roller 106 during such oscillation. At the opposite ends of cam surface 110 are respective cam surfaces 111, 112 of greater radial extent than depression 110, said cam surfaces upon engagement with cam roller 106 being adapted to depress plunger 104 and thereby to start rotation of motor 44 in the direction that lowers the scraper blade 61, which rotation continues until stopped automatically, after the blade engages the mill roll 12 and the spring 57 is compressed, by the torque-limit relay as previously explained. The cam surfaces 111, 112 are of relatively short linear extent, and contiguous with them are respective shallow depressions or relieved portions 113, 114 in the periphery of the cam 100. The surfaces 110 to 114 inclusive constitute about 165° of the total periphery of the cam, which, as previously stated, oscillates through an angle of 156°. When the cam is in such angular position that cam roller 106 is engaged with surfaces 113 or 114 thereof, the switch plunger 104 is slightly raised from its fully depressed position, but not sufficiently to effect driving of the motor to elevate the scraper blade. Thus there are shoulders formed on the cam at the juncture of surfaces 111, 113 and 112, 114 which shoulders readily pass the cam roller 106 when the cam is positively driven by the stud 98. If, however, due to inaccurate fitting or other cause, there is sufficient friction between the stud 98 and the marginal faces of slot 99 to cause the stud to drive the cam before the stud has reached the end of the slot, the resistance set up by engagement of the cam roller 106 with one of the shoulders aforesaid will be sufficient to overcome said friction and thereby to prevent further rotation of the cam until the stud reaches the end of slot 99.

In the operation of the apparatus, the mill rolls 11, 12 are set in motion in the usual manner, and a bank of rubber composition 14 is fed

into the bite of said rolls to effect the forming of a sheet or sleeve 13 of the composition upon the roll 12. Motor 28 is then set in motion to operate the carriage 22, the succeeding operations being automatically effected and the apparatus requiring no further attention. As the rubber composition becomes thoroughly mixed and warmed, portions of the sleeve 13 are cut therefrom for use in other rubber working apparatus, and as the bank of stock 14 becomes depleted, additional material is thrown into the bite of the rolls.

As the motor 28 rotates, the carriage 22 moves toward one end of the screw 24, then reverses its direction and moves toward the opposite end thereof, the blade 61 rising and descending at determinate points along the traverse of the carriage. The course of the blade 61 is best shown in Figure 7, the arrows indicating the direction of its travel. When the cam plate 78 is rotating in counterclockwise direction and is in the angular position shown in Figure 8, the blade 61 is at point A (Figure 7) of its course, bearing against roll 12 and moving toward the right. At this time cam 100 is in the position shown in Figure 11, the stud 98 already having moved this cam through 8°, the cam roller 106 still being in depression 114 of this cam. Continuing rotation of cam 100 in counterclockwise direction brings roller 106 onto cam surface 110 when the scraper blade 61 is at point B, Figure 7, of its traverse, with the result the switch plunger 104 rises and the switch 103 is operated to drive motor 44 in the direction that raises the scraper blade, rotation of the motor stopping when the blade is fully elevated. The blade continues to move laterally while in elevated position, and while the cam roller is still engaged with cam surface 110, the position of the latter and said cam roller as shown in Figure 12 corresponding to point C of Figure 7. Continued rotation of cam 100 in counterclockwise direction from the position shown in Figure 12 carries cam surface 110 beyond roller 106, the latter then engaging cam surface 111 which effects the depressing of plunger 104 and the reversing of the position of switch 103, with the result that motor 44 is set in motion in the direction that lowers scraper blade 61. After the blade engages the mill roll 12, the motor 44 again ceases rotating, the blade being at the position shown at D, Figure 7, and the cam 100 being substantially at the position shown in Figure 13, with cam roller 106 engaging cam surface 113. The carriage 22 continues to move to the right a short distance, until cam 89 on cam plate 78 engages and operates switch 85, as shown in Figure 9, thus reversing the motor 28, the position of the carriage 22 at this time being indicated at E, Figure 7. The movement of the carriage 22 toward the ends of its traverse may be cushioned by means of compression springs 116, 116 mounted upon the screw 24 at the opposite ends of its threaded portion, said springs also assisting the motor in initiating the reverse movement of the carriage.

Reversing of the motor 28 turns the screw 24 in the direction that impels the carriage 22 toward the left, and also reverses the direction of rotation of cam shaft 71 so that the latter, and cam plate 78 and the stud 98 then move in a clockwise direction. Stud 98 moves in the slot 99, relatively of cam 100, for 140°, and engages said cam just before the blade 61 reaches point F of its traverse, the position of cam 100 when the blade is at point F being shown in Figure 13.

The movements of the blade 61 at the left end of the machine are the same as those previously described at the right end of the machine, and at points G, H, I, and J, Figure 7, the blade follows a course identical to the course followed at points B to E, inclusive. When the blade is at point H, the cam 100 is substantially at the position shown in Figure 14 and moving in the direction indicated by the arrow. When the blade reaches point J, cam 81 will have moved to the position where it engages cam roller 92, as shown in Figure 10, to operate switch 86 and thus to reverse the motor 28 and thereby to move the carriage 22, in reverse direction, back to position A, the point of starting.

This completes a cycle of operation, which is continuous and automatic as long as motor 28 is in operation. The apparatus is superior in performance to similar apparatus of prior construction chiefly because its mechanisms are entirely electrically operated, thus obviating the use of fluid pressure operated devices. The use of a torque-limit relay for stopping rotation of motor 44 obviates the use of other stop switches and braking means, and the single spring 51 is utilized to provide the torque for stopping the motor when rotating in either direction.

Note that the movement, or course of the blade 61 can readily be varied. This is done by removing the nut holding the cam 100 on the shaft 71 and then inserting another pin in another hole 95a in the cam plate 95 whereby the permitted relative movement of the cam plate 78 and the cam 100 is changed and the vertical movement of the blade 61 is varied relative to its horizontal position on the mill. Another manner in which the movement of the blade 61 can be changed is to substitute a different cam for the cam 100 with the new cam having a different length arcuate slot and/or different length cam surfaces formed thereon whereby the vertical movement of the blade 61 relative to its transverse position on the mill could be varied.

Modification may be resorted to without departing from the spirit of the invention, or the scope thereof as defined by the appended claims.

What is claimed is:

1. In a mill of the character described, the combination of a scraper blade engageable with one of the mill rolls, a reversible feed screw having operative connection with the said blade for impelling it edgewise back and forth along the mill roll, a cam shaft, means for oscillating the latter through the agency of the reverse rotation of the feed screw, a second feed screw having operative connection with the scraper blade for raising and lowering it relatively of the mill roll, a reversible electric motor driving said second feed screw, a reversing starting switch in the electric circuit of said motor, said circuit including a torque-limit relay for stopping the motor, and cam means on the cam shaft for operating said starting switch after the first mentioned feed screw has made a determinate number of revolutions in either direction.

2. A combination as defined in claim 1 including means for increasing the torque on the motor as the blade reaches its fully raised or fully lowered positions.

3. In a mill of the character described comprising a scraper blade and means for moving it edgewise back and forth along a mill roll, the combination of a member connected to said blade and movable in an up and down direction for raising and lowering said blade relatively of the

mill roll, a motor for moving said member up and down, and means for increasing the torque on the motor as said member reaches determinate upper and lower limits.

4. In a mill of the character described comprising a scraper blade and means for moving it edgewise back and forth along the mill roll, the combination of an upright feed screw connected at its lower end to said blade, a reversible electric motor, means connecting the motor with the feed screw whereby the motor is enabled to effect axial movement of the feed screw in either direction to raise and lower the screw and blade, and means for increasing the torque on the motor as the blade reaches determinate upper and lower limits.

5. In a mill of the character described comprising a scraper blade and means for moving it edgewise back and forth along the mill roll, the combination of an upright feed screw connected at its lower end to said blade, a reversible electric motor, means connecting the motor with the feed screw whereby the motor is enabled to effect axial movement of the feed screw in either direction to raise and lower the screw and blade, a compression spring moving axially with said screw, and means for effecting compression of said spring as the screw reaches determinate upper and lower limits of movement as a means for increasing the torque on the motor.

6. In a mill of the character described comprising a scraper blade and means for moving it edgewise back and forth along a mill roll, the combination of an up and down slide to the lower end of which the scraper blade is attached, an upright feed screw having its lower end connected to said slide and having limited axial movement relatively thereof, a compression spring mounted upon said feed screw between said slide and a collar affixed to said screw, a nut engaging the upper end of said screw, and a reversible motor having driving connection with said nut, rotation of the latter in either direction effecting axial movement of the screw.

7. In a mill of the character described, the combination of a scraper blade engageable with one of the mill rolls, a rotary feed screw having operative connection with said blade for impelling it back and forth along said mill roll, a rotary cam shaft, speed reducing means between said feed screw and said cam shaft for driving the latter, cam means on the cam shaft for reversing the direction of rotation of the feed screw after it has made a determinate number of revolutions, means for raising and lowering said scraper blade relatively of the mill roll, cam means on the cam shaft controlling the operation of the last mentioned means in determinate time relation to the reversing of the feed screw, and means for effecting relative movement of the two cam means on the cam shaft.

8. A combination as defined in claim 7 in which the means for effecting relative movement of the two cams consists of a lost motion driving connection between the cam shaft and one of the cams thereon.

9. In a mill of the character described, the combination of a scraper blade engageable with one of the mill rolls, a rotary feed screw having operative connection with said blade for impelling it back and forth along said mill roll, a rotary cam shaft, speed reducing means between said feed screw and said cam shaft for driving the latter, cam means on the cam shaft for reversing the direction of rotation of the feed screw after it

has made a determinate number of revolutions, means for raising and lowering said scraper blade relatively of the mill roll, cam means on the cam shaft controlling the operation of the last mentioned means in determinate time relation to the reversing of the feed screw, said cam means on the cam shaft for controlling the

scraper blade operating means being adjustable whereby the determinate time of operating the scraper blade operating means with relation to the reversing of the feed screw can be varied, and means for effecting relative movement of the two cam means on the cam shaft.
